UNITED STATES PATENT OFFICE.

JOSEPH BOLESKA, OF ST. LOUIS, MISSOURI.

HORSE-COLLAR.

SPECIFICATION forming part of Letters Patent No. 367,950, dated August 9, 1887.

Application filed January 8, 1887. Serial No. 223,795. (No model.)

To all whom it may concern:

Be it known that I, JOSEPH BOLESKA, of St. Louis, in the State of Missouri, have invented a new and Improved Horse-Collar, of which 5 the following is a full, clear, and exact description.

Reference is to be had to the accompanying drawings, forming a part of this specification, in which similar letters of reference indicate 10 corresponding parts in all the figures.

Figure 1 is a rear elevation of my new and improved collar. Fig. 2 is a front elevation of the same. Fig. 3 is a section on line $x\ x$, Fig. 1; Fig. 4, a section on line $y\ y$, Fig. 1; 15 and Fig. 5 a section on line $z\ z$, Fig. 1.

The invention will first be described in connection with the drawings, and then pointed out in the claim.

A represents the front roll of the collar, and 20 B the pads, both stuffed in the usual manner. At the bottom of the front roll, A, is stitched in with the leather composing the pads B the diamond-shaped piece C of leather, and above this is stitched the flap D, which is stitched 25 at its edge to the pads, as shown in Figs. 1, 3, and 4. The leather C is also stitched to the

front leathers, b b, of the pads B. To the rear surface of the leather C is stitched the leather E. Between the upper edge of the leather E and the leather D the leather which forms the 30 pad B is bulged outward at F to form a cushion, F', which serves to protect the horse's throat and prevent him from being choked, which is the principal object of my invention.

By the construction described the collar is 35 also made very strong and at the same time flexible at the bottom, so that it can be easily passed over the horse's head for putting the collar on and removing it.

Having thus described my invention, what I 40 claim as new, and desire to secure by Letters Patent, is—

A horse-collar formed with two intermediate pieces, C D, at the bottom of the collar, in combination with the cushion F', and backing-piece E, substantially as and for the purposes set forth.

JOSEPH BOLESKA.
